UNITED STATES PATENT OFFICE.

OLINTHUS G. ALDERMAN, OF TRAER, IOWA.

MECHANICAL MOVEMENT.

SPECIFICATION forming part of Letters Patent No. 254,186, dated February 28, 1882.

Application filed May 28, 1881. (Model.)

To all whom it may concern:

Be it known that I, OLINTHUS G. ALDERMAN, of Traer, in the county of Tama and State of Iowa, have invented certain new and useful Improvements in Mechanical Movements; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

This invention relates to mechanical movements, the object being to provide improved devices for converting motion; and the invention consists in the construction and arrangement of parts, as hereinafter more fully described and claimed.

In the annexed drawings, Figure 1 is a front elevation of my improved devices for converting motion. Fig. 2 is a side view of the same, partly in section. Fig. 3 is a perspective view of the crank-wheel with sliding bar and pitman, and Fig. 4 is a modification.

Like letters indicate like parts.

A represents one of the bearings of a power-shaft, B, which carries a crank-wheel, C. The face of this wheel is transversely grooved at the center, the said groove having beveled sides for the reception of a correspondingly-shaped sliding bar, D, which is thus keyed to the wheel so as to reciprocate within the groove at each revolution of the wheel.

At one end of the sliding bar D is a wrist-pin, to which the pitman E is attached. This wrist-pin also carries a roller, F, which engages in an elliptical groove or slot, G, formed in a face-plate, H, which is provided with a shank or arm, H', that is attached to the standard or bearing A by means of suitable screws or bolts.

When power is applied to the crank-wheel B, causing it to revolve, it will be seen that the engagement of the roller F in the elliptical slot or groove G causes the sliding crank-bar D to move back and forth in the transverse groove across the wheel, thus practically equalizing the length of the pitman E and enabling

it to push or pull more evenly and with less strain. By making the sliding bar D of such length that it extends across the wheel C a steady motion is imparted to the pitman E, the

ends of which at each reciprocation describe ellipses.

Instead of forming the elliptical groove or slot G in the face-plate H, said plate may be dispensed with and an elliptical groove made in the bearing A, through the center of which passes the shaft B. In this instance the shaft B may carry a wheel having a transverse groove; as above described, with a notch or recess cut through the wheel at one end of the groove; or a crank-bar, C', may be substituted for the wheel, as shown in Fig. 4. This bar is grooved longitudinally for the reception of a sliding bar, D, having a wrist-pin, d, at one end for attachment of the pitman, and at the same end of the sliding bar, on the opposite side, is a roller, that passes through a notch or recess, e, in the end of the bar C' and engages with the elliptical groove in the bearing A, the operation of the modified devices and the effect produced upon the pitman being the same as that before described.

What I claim as my invention is—

1. In a mechanical movement, the combination, with a transversely-grooved wheel attached to the end of a driving-shaft journaled in suitable bearings, of a face-plate or bearing having an elliptical groove or slot, a sliding bar reciprocating within the grooved face of the wheel at each reciprocation of the same, and provided with a roller adapted to engage with the elliptical groove or slot, and a pitman attached to the sliding bar, whereby the movements of the pitmen are equalized and an elliptical motion imparted to its ends at each reciprocation, substantially as specified.

2. In a mechanical movement, the combination, with the transversely-grooved wheel C, attached to a driving-shaft, B, journaled in the bearing A, and a face-plate, H, having an elliptical slot or groove, G, and shank H', by which it is attached to the bearing A of the sliding crank-bar D, carrying a pitman, E, and a roller, F, adapted to engage with the elliptical groove in the face-plate, substantially as and for the purpose shown and described.

In testimony that I claim the foregoing as my own I have hereto affixed my signature in presence of two witnesses.

OLINTHUS G. ALDERMAN.
